No. 738,370.

PATENTED SEPT. 8, 1903.

J. C. W. STANLEY.
ATTACHMENT FOR COTTON GINS.

APPLICATION FILED AUG. 6, 1902.

NO MODEL.

UNITED STATES PATENT OFFICE.

JOHN C. W. STANLEY, OF LONDON, ENGLAND, ASSIGNOR TO THE COTTON SEED COMPANY, LIMITED, OF LONDON, ENGLAND.

ATTACHMENT FOR COTTON-GINS.

SPECIFICATION forming part of Letters Patent No. 738,370, dated September 8, 1903.

Application filed August 6, 1902. Serial No. 118,663. (No model.)

To all whom it may concern:

Be it known that I, JOHN C. W. STANLEY, a subject of the King of England, residing at London, England, have invented certain new and useful Improvements in Attachments for Cotton-Gins, of which the following is a specification.

This invention relates to cotton-gins, and particularly to an improved attachment for facilitating the discharge of the seeds from the ginning-chamber.

In ginning seed-cotton, as ordinarily practiced, it is subjected to the action of the saws until almost all of the lint is torn from the seed, and consequently there is considerable short fiber or fuzz mixed with the long fiber, and this tends to lower the grade of the cotton. If any considerable quantity of short fiber is left upon the seeds, they will mat or ball together and cannot escape from the ordinary cotton-gin, which is usually provided with a grating through which the seed passes, and for this reason it has been necessary to subject the seed to the action of the saws until almost all of the short fiber is removed from them.

The object of my invention is to provide means for the escape of the seeds before very much of the short fiber is separated or torn from them by the saws, and so obtain a high grade of cotton practically free from short fibers. The short fiber remaining on the seed can be subsequently removed from the seed by running it through another gin or a de-linter.

The invention will be fully described hereinafter, reference being had to the accompanying drawings, in which—

Figure 1 is a perspective view of an ordinary cotton-gin and of my attachment thereto. Fig. 2 is a sectional view of the ginning-chamber.

The cotton-gin is indicated as a whole by A and may be of any preferred form, and it is unnecessary to describe it in detail except so far as may be required to illustrate the application and mode of operation of my attachment. The ginning-chamber is indicated by B, and the saws by b. The ribbed breast

5 a cross-beam a of the frame of the machine. D is the breast-board, rigidly attached to the end castings E, which are hinged to the frame at their upper rear corners, as indicated at e. Each end casting is provided at its lower end with a lug or extension x, which normally engages the fall-board c. To the lower edge of the breast-board D a grating d is attached and projects into close proximity with the ribbed breast C. All these features are common and well known in cotton-gins.

In ginning seed-cotton, as is well known, the seed-cotton forms into a roll and all the long fiber is removed by the saws through the upper portion of the ribbed breast C, and the seeds, with the short fiber still adhering to them, drop down into the comparatively narrow space (indicated by b') between the breast-board D and the saws, and almost all of the short fiber must be removed from them in that space before the seed can pass through the grating d. All this short fiber is necessarily mixed with the long fiber, and consequently lowers the grade of the cotton. Now, as before stated, the object of my invention is to prevent this mixture of long and short fiber, and to accomplish this it is necessary to remove the seed from the action of the saws before the latter have a chance to remove much of the short fiber, and to accomplish this it is necessary to increase the area of the exit for the seed. This may be accomplished in various ways; but preferably I provide means for intermittently opening the breast-board D to a predetermined extent to permit the seeds to escape. Thus I provide a wheel G on a shaft g, supported in bearings h on a frame, (indicated as a whole by H.) The shaft g also carries a gear-wheel I, which meshes with a pinion K, carried by a shaft k, also supported in bearings on the frame H, and this shaft may be driven from any source of power. (Not shown.) The gearing and speed of the shaft k will preferably be so proportioned that the wheel G will have about sixty revolutions per minute; but I do not restrict myself in this respect, as it may sometimes be advisable to increase or diminish this speed very materially. The wheel G carries on its periphery a lug l, adapted to engage a similar lug m on a bar or rod M,

supported to slide in bearings *n* on the frame *H*, and a cord or wire *o* leads from the bar *M* to the breast-board *D*, to which it is attached. At each revolution of the wheel *G* the bar *M* will be moved longitudinally to the left and the breast-board *D* will be opened correspondingly, and thus permit the partially-delinted seed to drop out. The extent of this opening will vary in accordance with the character of the cotton being treated. In practice I have found one-inch-and-a-half opening of the breast-board to be very satisfactory in ginning Indian cotton, which is a short staple and small-seeded cotton. With American cotton it will be desirable to increase the extent of the opening and possibly the frequency of the openings, owing to the larger size of the seed, and in order to be able to vary the extent of such opening of the breast-board *D*, I make the connection of the lug *m* to the bar *M* adjustable, so that by shifting the lug *m* on the bar *M* the length of time of its engagement with the lug *l* on the wheel *G* may be varied, and consequently the extent of movement of the bar *M* and of the breast-board *D* will be varied. The means for effecting the adjustment of the lug *m* may vary, and as illustrating one means I have shown the lug *m* as being provided with a threaded stem *10*, extending through a slot *11* in the bar *M* and provided with a clamping-nut *12*; but I do not limit myself to this special means of adjustment. Whatever the extent of the opening the lug *l* will suddenly become disengaged from the lug *m*, and thereby release the bar *M*, and the weight of the fall-board *D*, which is considerable, will cause it to close rapidly, and the impact of the projections *x* on the fall-board *c* will impart a jar to the gin, which will greatly aid in separating the partly-delinted seed from the cotton-roll, so they can pass down into the space *b*. The bar may be provided with any suitable device—as, for instance, a pin *15*—to limit its movement toward the gin when the breast-board closes.

Without limiting myself to the precise construction and arrangement of parts shown and described, I claim—

1. The combination with a cotton-gin having a hinged breast-board, of means supported independently of the gin but connected to the breast-board and movable to open it intermittently to a predetermined extent, substantially as set forth. 50

2. The combination with a cotton-gin having a hinged breast-board, of a reciprocating device supported independently of the gin and connected to the breast-board, and means for reciprocating said device intermittently 60 to open the breast-board, substantially as set forth.

3. The combination with a cotton-gin having a hinged breast-board, of a bar supported to slide in bearings and connected to the 65 breast-board, and means for intermittently moving the bar in one direction to open the breast-board, substantially as set forth.

4. The combination with a cotton-gin having a hinged breast-board, of a bar supported 70 to slide in bearings and connected to the breast-board, means for intermittently moving the bar in one direction to open the breast-board, and means for varying the extent of movement of the bar, substantially as set 75 forth.

5. The combination with a cotton-gin having a hinged breast-board, of a bar supported to slide in bearings and connected to the breast-board, a lug on the bar, and a rotating 80 wheel carrying a lug to engage the lug on the bar and move the bar to open the breast-board, substantially as set forth.

6. The combination with a cotton-gin having a hinged breast-board, of a bar supported 85 to slide in bearings and connected to the breast-board, a lug adjustably supported on the bar, and a rotating wheel carrying a lug to engage the lug on the bar and move the bar to open the breast-board, substantially as 90 set forth.

In testimony whereof I have signed my name to this specification in the presence of two subscribing witnesses.

JOHN C. W. STANLEY.
